ONE-WAY HINGELESS VENTILATOR
Timothy A. Kelly, 423 Market St., Salem, Va. 24153,
and David R. Altice, 3201 Ventor Road SW., Roanoke,
Va. 24000
Filed July 1, 1966, Ser. No. 562,228
6 Claims. (Cl. 98—2)

This invention relates to a hingeless ventilator for ventilating enclosed air spaces.

The primary object of the invention is to provide an improved ventilator having a cover which, without a hinged connection to its mount, can be swung in an arc about one extremity of an opening to which it is applied and will be held effectively against service shocks either in closed position or at any point along the arc.

Another object of the invention is to provide a hingeless ventilator wherein the cover is connected to its mount by a stationary tension spring, which not only prevents accidental removal of the cover but supplies the force by which the cover is held in any position in which it is set.

An additional object of the invention is to provide a hingeless ventilator of such arrangement and construction that the same stationary tension spring is enabled to apply to the cover a force in a closing direction in closed position and mainly in a different direction over the range of movement of the cover between opened and closed positions.

A further object of the invention is to provide a hingeless ventilator which is rugged and economical in construction, has a long service life, and in closed position effectively seals the opening to which it is applied.

Other objects and advantages of the invention will appear hereinafter in the detailed description, be particularly pointed out in the appended claims and be illustrated in the accompanying drawings, in which:

FIGURE 1 is a plan view of a preferred embodiment of the hingeless ventilator of the present invention with its cover in closed position;

FIGURE 2 is an end elevational view of the ventilator of FIGURE 1 with the cover in open position;

FIGURE 3 is a side elevational view of the structure of FIGURE 2;

FIGURE 4 is a vertical sectional view on an enlarged scale, taken along lines 4—4 of FIGURE 1;

FIGURE 5 is a fragmentary vertical sectional view on the scale of FIGURE 4, taken along lines 5—5 of FIGURE 1;

FIGURE 6 is a fragmentary view on the scale and section of FIGURE 5, but with the cover in open position; and

FIGURE 7 is a fragmentary vertical sectional view on the scale of FIGURE 4, taken along lines 7—7 of FIGURE 1.

Referring now in detail to the drawings, in which like characters designate like parts, the improved hingeless ventilator of the present invention, while applicable generally for ventilating enclosed air spaces by regulating the flow of forced air to or from such spaces, is particularly adapted for ventilating a cab or other enclosed space of a vehicle in which the flow of air is produced by movement of the vehicle.

The improved ventilator may be installed on a horizontal or other wall 1 of an enclosed space (not shown) and, when that space is a cab or compartment of a vehicle, may be positioned to open forwardly or rearwardly, depending on whether air is to be forced into or drawn out of the space by the vehicle's movement. The ventilator is comprised of a cover, door or closure member 2, a frame 3 bounding an opening 4 closable by the cover, and a tension rod or spring 5 stationarily mounted on the

2

frame for holding the cover in position. Depending on the installation, the frame 3 may be integral with the wall 1, or, as illustrated, an initially separate member weldable or otherwise fixable to the wall and installable as a unit 5 with the cover 2 in an aperture 6 cut or otherwise formed in the wall.

Whatever the installation, the cover 2, despite lack of any direct connection to the frame 3, is designed to swing or pivot between opened and closed positions about a substantially fixed axis or fulcrum and to be held in those positions and positions therebetween by tensioning or flexing of the rod 5. This operation is obtained by providing at least one end or extremity of the opening 4 in the frame 3 an outstanding or outwardly projecting stop or 10 abutment 7, and on the cover 2, and instanding or inwardly directed shoulder or abutment 8 overlapping and engageable with the outer side of the stop. Conveniently, the stop 7 is part of a continuous, outstanding or outwardly projecting lip or flange 9 on, integral or rigid with the frame 3 and bounding or extending about the opening 4, while the shoulder 8 is part of a continuous instanding or inwardly directed peripheral skirt or flange 10 on, integral or rigid with the cover 2. With the cover 2 and opening 4 of the preferred generally rectangular shape, 15 there thus are provided at the end of the opening 4 about which the cover 2 is adapted to swing, a pair of cooperating abutments 7 and 8 which constantly overlap and, under a force urging the cover abutment both toward the frame abutment and inwardly normal to the opening 4, 20 will engage or contact along a substantially straight line that will be either fixed or substantially fixed, depending on the spacing in closed position between the cover abutment and the outer side or surface 11 of the frame 3 beyond the frame abutment. For minimizing shifting of 25 the swinging axis in the illustrated embodiment by outward sliding of the adjacent cover flange 10 along the frame flange 9, the latter conveniently has stamped or otherwise formed on it a plurality of laterally spaced positioning or bearing lugs 12 outstanding toward and engageable by the cover flange 10.

To make the line of contact between the pair of abutments 7 and 8, at the end or extremity of the opening 4 about which the cover 2 swings, the at least substantially fixed swinging axis or fulcrum of the cover, the rod 5 is 30 stationarily mounted on the opposite or inner side or surface 13 of the frame 3, laterally or transversely of the opening and intermediate and preferably substantially midway of the opening's longitudinal extremities or confines, with its axis substantially parallel to space inwardly 35 from the swinging axis of the cover 2. For both connecting it to the frame 3 and applying to it throughout its range of movement the force of the rod 5, the cover 2 has a handle, lever or guide 14 fixed or secured to it and projecting inwardly from its inner face 15 through the opening 4. On the handle 14 is a guideway or guide surface 16 which slidably engages the rod and in the main faces toward the cover's hinging axis and flexes or bends the rod in the same direction on swinging of the cover 40 between opened and closed positions. If, as in the illustrated embodiment, the tension rod 5 extends across the opening 4 and is fixed at, rather than intermediate, its ends, as by brackets or retainers 17 welded or otherwise fixed or secured to the inner surface 13 of the frame 3 at opposite sides of the opening, the handle 14 is substantially centered laterally of the opening so as to bend, flex or tension the rod substantially at the latter's middle and avoid imbalance in the resultant force on the cover.

The illustrated handle 14 is simple but effective. It has a body 18 that is flat longitudinally of the opening 4 and that has the guideway 16 formed in it as part of a slot 19. Its inner end is bent at right angles to the body 18 to pro-

vide a foot or mounting flange 20 for riveting or other connection, either directly or through an interposed spacer block 21 to the cover 2, and for convenient handling, it has at the outer end of its body a threaded head 22 for mounting a knob or grip 23. Rigid and perpendicular to the cover 2, the body 18 suitably may be generally of S-shape to contain the guideway 16 with a minimum of metal. Both the guideway 16 and the slot 19 are arcuately concave and, except adjacent its outer or cover end, the guideway presents to the side of the rod 5 it engages a smooth, uninterrupted circularly or cylindrically concave surface or track 24 which is bounded inwardly by the slot's concave inner end wall 25. Struck substantially about the swinging axis of the cover for uniformity of the holding force, the surface 24 is of a radius to cause the rod to bend, flex or tension toward that axis to such an extent that the consequent frictional resistance to relative movement between the rod 5 and the handle 14 will suffice to hold the cover against accidental dislodgement by service shocks in any position in which it is set beyond closed position. Not only does the flexing of the rod 5 hold it frictionally at any point along the track 24 and yieldably resist swinging of the cover 2 from the position in which it is set, but, since the resultant force on the cover abutment 8 is directed from the swinging axis toward the axis of the rod at an inward incline or slope, there is at all times an inward component which holds the cover 2 firmly against the frame.

Beyond the outer or cover end of the circular track 24, the guideway 16 is indented away from the end of the opening 4 about which the cover 2 swings, to form a socket or pocket 26 in which the rod 5 seats in the closed position of the cover. The socket or notch 26 is of such depth and so spaced inwardly from the inner face 15 of the cover 2 that the entrant portion of its wall serves as a cam or camming surface 27 which cams the rod as it leaves the track 24 in a closing operation, so as to change the flexing, bending or tensioning of the rod 5 from a direction toward the swinging axis of the cover to one toward and substantially normal to the cover's inner face. Thus, when in the closed position of the cover 2 the rod 5 is fully seated in the socket 26, the force applied by the rod is substantially entirely an inward force that holds the cover tightly against the frame 3 around the entire opening 4.

If the cover 2 and frame 3 are installed as a unit, the position in which the frame is applied to the wall 1 of the enclosed spaced to be ventilated will determine in which direction the cover will open. The same versatility is provided, even when the frame is integral with the wall 1, so long as there are at least frame abutments 7 at both ends of the opening. Also, if this last requirement is met, a ventilator, once installed, can be changed to open in the opposite direction simply by detaching one of the brackets 17, sliding the rod 5 out of the other bracket and reanchoring the ends of the rod to the frame 3 after the rod and cover have been turned 180°.

At least in a vehicle installation in which the opening 4 should be sealed against the elements when the cover 2 is closed, the inner face 15 of the cover preferably is lined with a resilient liner or pad 28 of rubber or like material. The positive closing force exerted by the rod 5 on the cover 2 in the latter's closed position enables the liner 28 to be made of material that is harder than the usual ventilator sealing gasket and will not absorb moisture, the presence of which would contribute to the deterioration of the ventilator and its surroundings. The preferred liner 28 also substantially fully covers the inner face 15 of the cover 2 for a better and more permanent seal than the usual strip gasket can afford.

While in the illustrated embodiment the cover 2 is

adequately positioned or located laterally of the opening 4 by the overlap or interfit at the sides between the frame and cover flanges 9 and 10, if desired, a locating plate 29 slotted to pass the handle 14 and extending longitudinally across the opening 4, may be secured to the inner side 13 of the frame 3 at opposite ends of the opening, and this plate and the mounting brackets 17 conveniently may be provided with tabs 30 for mounting screens 31 in the opening to keep out insects when the cover is open.

From the above detailed description it will be apparent that there has been provided an improved one-way hingeless ventilator, the cover of which can be set in any desired position within its range of movement and will hold that position against accidental dislodgement by any force to which it is subjected in service. It should be understood that the described and disclosed embodiment is merely exemplary of the invention and that all modifications are intended to be included that do not depart from the spirit of the invention and the scope of the appended claims.

Having described our invention, we claim:

1. A one-way hingeless ventilator comprising a frame bounding an opening, a cover swingable on said frame for opening and closing said opening, guide means fixed to said cover, tension rod means fixed to said frame and slidably engaging and tensioned by said guide means for connecting said cover to said frame and determining the extent of opening of said cover, and means on said frame and cover and operative on swinging of said cover for substantially fixing the swinging axis thereof.

2. A one-way hingeless ventilator according to claim 1, wherein the guide means projects through the opening and the tension rod means are fixed to a side of the frame opposite the cover.

3. A one-way hingeless ventilator according to claim 2, wherein there are guideway means on the guide means, the tension rod means are stationarily mounted on the side of the frame opposite the cover and slidably engage and are tensioned by said guideway means, and said guideway means is struck in part substantially about the hinging axis for tensioning the rod means toward the axis during swinging of the cover.

4. A one-way hingeless ventilator according to claim 3, including cam means on the guideway means for tensioning said rod means substantially toward said cover on closing thereof.

5. A one-way hingeless ventilator according to claim 4, wherein the guide means are handle means for swinging the cover between opened and closed positions.

6. A one-way hingeless ventilator according to claim 5, wherein there is a slot in the handle, the guideway is in said slot, the tension rod is received in said slot, the part of the guideway struck substantially about the axis is removed from the cover, there is a socket in the guideway adjacent said cover for seating the rod in the closed position of the cover, and the cam means are cam surface means in an entrant portion of said socket for changing the direction of tensioning of the rod in a closing operation as the cover approaches closed position and tensioning the rod in said position toward the substantially normal to said cover.
